UNITED STATES PATENT OFFICE.

ABRAHAM CALVERT SCARR, OF HARRISTON, CANADA, ASSIGNOR OF ONE-HALF TO DANIEL DAY SMITH, OF HAMILTON, ONTARIO, CANADA.

WHIFFLETREE.

SPECIFICATION forming part of Letters Patent No. 732,320, dated June 30, 1903.

Application filed April 24, 1903. Serial No. 154,094. (No model.)

To all whom it may concern:

Be it known that I, ABRAHAM CALVERT SCARR, a citizen of Canada, residing at Harriston, in the county of Wellington and Province of Ontario, Canada, have invented certain new and useful Improvements in Whiffletrees, of which the following is a specification.

My invention relates to improvements in whiffletrees for vehicles; and it principally consists of the hollow metallic construction of the doubletree and the swingletrees, which comprise the whiffletree.

The object of my invention is to provide a hollow metallic whiffletree which shall combine strength, durability, and lightness. I attain this object by the device illustrated in the accompanying drawings, in which—

Figure 1 is a plan of my improved whiffletree in its completeness. Fig. 2 is an enlarged plan of one end of the doubletree. Fig. 3 is an enlarged plan of one end of a swingletree. Fig. 4 is an enlarged sectional end elevation of the doubletree through a central part thereof, showing also the section of a wood block, the swingletrees being similar. Fig. 5 is an enlarged plan of the central part of the doubletree, the upper plate being broken away to show the wood block in the interior, the swingletree being similar. Fig. 6 is an enlarged sectional end elevation of a doubletree or a swingletree of modified construction of a single piece of sheet metal.

Similar letters refer to similar parts throughout the several views.

In the drawings the doubletree is indicated by A and the swingletrees by B. At each end of the doubletree is a clevis 2, pivotally connected at 3 to a rear plate 4. The central part of the swingletree B is provided with a staple-eyebolt 5, which extends through the swingletree and fastens thereto against a washer-plate 6. The clevis 2 is adapted to allow the rear eye part of the staple-bolt 5 to swivel therein. The ends of the swingletrees B are provided with U-shaped closed end plates 7, which cover the ends of the swingletrees and extend a suitable distance on the front and the rear sides thereof and flush with the swingletree. The clevis-hooks 8 near each end of the swingletrees are pivotally connect-

ed at 9 to the rear part of the U-shaped plates 7. The clevis-plates 4 and 7 are bolted or riveted to their respective parts of the whiffletree, as is desired.

10 is an eyelet-plate secured to the front central part of the doubletree for attachment to a vehicle, and the clevis-hooks 8 of the swingletrees are for attachment of the horse side straps.

The important part of my invention consists of the metallic construction of the doubletree A, together with the swingletree B, the top and the bottom of each being of a single thickness of metal and the sides thereof— that is, the front and the rear—are of double thickness of metal and secured together, as especially shown in Fig. 4 of the drawings.

The metallic doubletree, together with the metallic swingletrees, are formed with a horizontal top plate 12 with side flanges 13 at about right angle thereto and forming one single piece of metal. The bottom or under side 14 of the doubletree, together with the swingletrees, are formed with side flanges 15, which fit snugly into and between the side flanges 13 of the upper part. The side flanges 13 and 15 may be secured together at approved places by means of rivets 16. (Shown in Fig. 4 of the drawings.)

The closed U-shaped end plate 7 of the swingletrees may be applied to the ends of the doubletree, if deemed expedient.

It will be obvious that the doubletree and the swingletrees are of similar construction, though differing in size and proportion.

The central part of the doubletree and the swingletrees are provided with suitable blocks of wood 18, which may be six or eight inches in length, more or less, in full-size whiffletree, in order to strengthen the middle part thereof, more especially in the doubletree part. The wood blocks 18 referred to are advantageous when the whiffletree is constructed of light material. When the wood blocks are applied in the whiffletree, the construction of the whiffletree may be of lighter material, thereby adding no additional weight in obtaining the desired results—that is, sufficient strength with a minimum of weight of whiffletree.

It will be noticed that the upper part or top 12 of the whiffletree, together with the sides

13, entirely cover the exposed parts thereof, thereby presenting in appearance one solid piece of metal without joint or opening to the weather. This feature is important.

- 5 It will be obvious that throughout the body of the whiffletree the upper and the lower body parts 12 and 14, respectively, is each of single thickness of metal and that the sides or flanges thereof, 13 and 15, respectively, 10 when in position form a double or two thicknesses of metal, thereby adding great strength to said sides—that is, to the front and to the rear of the whiffletree. This feature is desirable in a whiffletree and especially so in the 15 front part thereof. The metallic section throughout the whiffletree from end to end is similar and of identical construction, comprising upper and lower single plates and the front and rear sides of double plates.
- 20 In Fig. 6 of the drawings is shown a sectional end elevation of a lighter whiffletree, consisting of a continuous single piece of metal comprising the top 20, the bottom 21, the rear side 22, and the front side 23, which 25 is double. The rear side 22 is of a single thickness of metal continued at right angle from the top 20, and the interior flange 24 is continued from the bottom 21, which is a continuation from the rear side 22 and is parallel 30 with the top 20. The flange 24 extends to the top plate 20 on the inner side of the front 23, thereby presenting a single thickness of metal to the top, a single thickness to the rear side, and a single thickness to the bottom side and 35 two thicknesses of metal to the front side of the whiffletree. The block 18 in this section of a whiffletree, as shown in Fig. 6 of the drawings, is similar to the block 18, as shown in Fig. 4 of the drawings, and for the same purpose of strengthening the whiffletree in the 40 central parts thereof.

Various changes in the form, proportion, and minor details of this invention may be resorted to without departing from the spirit 45 and scope thereof.

What I claim as my invention, and desire to secure by Letters Patent, is—

1. A whiffletree for vehicles, comprising a horizontal top plate with sides extending 50 downward, a horizontal bottom plate with sides extending upward and adapted to fit be-

tween the sides of the top plate and fasten therein, substantially as set forth.

2. A whiffletree comprising horizontal upper and lower plates, side flanges extending 55 downward from the upper plate and side flanges extending upward from the lower plate, said flanges of the lower plate adapted to fit between the flanges of the upper plate, substantially as set forth.

3. A metallic whiffletree comprising an upper plate and a lower plate; sides extending from said plates and adapted to fit one against the other whereby each said side shall comprise two thicknesses of material, substantially as set forth.

4. In a whiffletree of the class described, a U-shaped plate adapted to fit over the end of the whiffletree and fasten thereto and a clevis pivotally connected to the rear side of 70 said plate, substantially as set forth.

5. In a whiffletree an upper plate with downwardly-extending sides, a lower plate with upwardly-extending sides adapted to fit between the downwardly-extending sides and 75 fasten thereto, and a block adapted to fit between said sides, and fasten thereto, substantially as set forth.

6. In a whiffletree a top plate, a rear side extending downward from the plate, a bottom 80 continued from said side and parallel with the top, a front flange extending downward from the opposite side of the top plate, and an upward continuation from the bottom plate and adapted to fit against the inner side of 85 said front flange and fasten thereto, substantially as set forth.

7. In a whiffletree an upper horizontal plate, a lower plate parallel therewith, a rear plate forming a part of the same, a front side continued from the upper plate, a flange continued from the lower plate and adapted to fit against the inner part of the front side, and a block inclosed between said sides, substantially as set forth.

In testimony whereof I affix my signature in presence of two witnesses.

ABRAHAM CALVERT SCARR.
